PRESSING IRON

Ivar Jepson, Oak Park, Ill., assignor to Sunbeam Corporation, Chicago, Ill., a corporation of Illinois

Filed May 2, 1960, Ser. No. 26,308

10 Claims. (Cl. 38—77)

The present invention relates generally to pressing irons, and, more particularly, to a pressing iron capable of readily being converted to a steam iron so that it may serve equally well as a steam or dry iron.

Irons of this type comprise a water reservoir and a valve mechanism for controlling the flow of water to a steam generating chamber, preferably located in the sole plate, at a rate of flow which allows the water to be flashed almost instantly into steam. Hence, this type of steam iron is conventionally referred to as of the flash type. The generated steam is distributed through the material being ironed or steamed by means of ports or the like which communicate with the steam generating chamber and open on the ironing surface of the sole plate. Irons of this type are usually provided with thermostatic means responsive to the temperature of the sole plate and adjustable to maintain the sole plate at a selectively controlled temperature, depending upon the material to be ironed. In steam irons of the flash type presently available on the market, the water reservoir is commonly spaced directly above the sole plate and below the handle of the iron. Steam irons of this type customarily include manual means for controlling the flow of water to the steam generating chamber and also include manual means for controlling the temperature of the iron. Thus, in such prior devices, the supports for the cover shell and the handle conventionally extend through or are attached to the reservoir, and, in addition, the reservoir is provided with numerous openings through which the flow control mechanism and the temperature control means extend.

It is also known to locate the water reservoir at least partially within the handle or handle supporting columns of the iron. Such arrangements have not been entirely satisfactory in that the steam and temperature controls have not been conveniently located and the reservoir construction is complex creating a high cost of manufacture. Moreover, it is desirable to provide a handle construction and water reservoir wherein a minimum number of heat conducting elements extend from the sole plate to the handle so that the handle does not tend to get uncomfortably hot.

The size of the water reservoir included in steam irons now available generally causes the irons to be bulky with the result that such irons do not present a pleasing appearance. It would be desirable to provide a combined steam or dry iron which is substantially of the same size as an ordinary dry iron while still providing a reservoir of large capacity. It would, of course, be desirable to provide an iron possessing small outside dimensions comparable to those of the ordinary dry iron while having the component elements organized in such a manner that a minimum transfer of heat occurs between the sole plate and the handle while at the same time having the necessary water capacity of convenient use as a steam iron. In pressing irons of the type described above, the number of the elements constituting the temperature control means are frequently located directly above the sole plate in the most crowded portion of the iron and preferably including an operating arm extending upwardly and into the handle of the iron in order to facilitate fingertip adjustment of the temperature. In prior Patent No. 2,906,043 Jepson and Vieceli, granted September 29, 1959, and assigned to the same assignee as the present

2

application, there is disclosed one arrangement wherein the temperature control means is located to provide for more effective utilization of the space between the sole plate and the reservoir while at the same time preventing the heat transmitted to the reservoir from adversely affecting the operation of the thermostatic switch. A thermostatic control means is desirable which is adequately compensated for ambient temperatures and which is readily controllable by heat control means near the handle of the iron.

In irons of the type discussed above, the temperature control means frequently include manually adjustable means and an associated temperature dial capable of being set to different operating temperatures indicated by suitable indicia on the dial and each corresponding to a particular type of material to be ironed. At the time of manufacture and occasionally afterwards the dial setting may not correspond exactly to the iron temperature with the result that improper heat is applied to the material being ironed. As a consequence, it becomes necessary to provide for initial and sometimes later calibration of the temperature control means in order to obtain correlation between the temperature dial setting and the operating temperature of the sole plate. In the devices of the prior art, such calibration has frequently been possible only by disassembly of a portion of the iron, a process which is both laborious and time-consuming. In the above mentioned Jepson and Vieceli patent, there is disclosed a means of calibrating the temperature control means by an adjustment accessible through the front post of the handle. It would be desirable to provide the calibration of the temperature control means by a yet more readily accessible adjustment available from the exterior of the iron. Moreover, such an adjustment should be inexpensive, sturdy and reliable.

Accordingly, it is an object of the present invention to provide a new and improved iron of the character described above.

It is also an object of the present invention to provide a new and improved temperature control means which may be calibrated through an adjustment readily accessible from the exterior of the iron.

A further object of the present invention is to provide a steam iron having an improved water reservoir means within the handle thereof.

Still another object of the present invention is to provide a steam and dry iron having maximum water capacity without substantially increasing the size of the iron over that of conventional pressing irons by providing a compact structural arrangement of the handle and water reservoir.

It is a further object of the present invention to provide improved and novel structure for securing the handle to the sole plate of an iron.

The invention further resides in various structural improvements and innovations in the device by virtue of which efficiency and simplicity of operation are combined with low manufacturing cost and foolproof operation, of which structural features may be particularly

mentioned the novel manner in which the water reservoir is located within the handle of the iron, the compact arrangement of the temperature and steam controls, the ease by which these controls may be utilized, the manner in which the thermostatic control mechanism is mounted on the sole plate, and the improved arrangement of various parts thereby insuring simplicity, minimum transfer of heat to the handle of the iron, ease of assembly and disassembly, and low manufacturing cost.

Further objects and advantages of the present invention will become apparent as the following description proceeds, and the features of novelty which characterize the invention will be pointed out with particularity in

the claims annexed to and forming a part of this specification.

For a better understanding of the present invention, reference may be had to the accompanying drawings in which:

FIG. 1 is a perspective view of a pressing iron embodying the features of the present invention;

FIG. 2 is an enlarged longitudinal sectional view taken substantially along the center line of the iron of FIG. 1 and showing the steam flow control valve in the closed or "steam off" position;

FIG. 3 is a sectional view taken substantially along line 3-3 of FIG. 2, assuming that FIG. 2 shows the complete structure;

FIG. 4 is a fragmentary sectional view taken substantially along line 4-4 of FIG. 2, again assuming that FIG. 2 shows the complete structure;

FIG. 5 is a fragmentary sectional view taken substantially along line 5-5 of FIG. 2, also assuming that FIG. 2 shows the complete structure;

FIG. 6 is a partial sectional view taken along line 6-6 of FIG. 2, assuming that FIG. 2 shows the complete structure;

FIG. 7 is a sectional view taken along line 7-7 of FIG. 2, assuming that FIG. 2 shows the complete structure;

FIG. 8 is a sectional view of the pressing iron of FIG. 1 taken along line 8-8 of FIG. 2 again assuming that FIG. 2 shows the complete structure;

FIG. 9 is a fragmentary sectional view taken along line 9-9 of FIG. 8;

FIG. 10 is a sectional view taken substantially along line 10-10 of FIG. 2, assuming that FIG. 2 shows the complete structure;

FIG. 11 is a plan view of the sole plate of the iron of FIG. 1; and

FIG. 12 is a circuit diagram indicating schematically the electrical control circuit embodied in the pressing iron of FIG. 1.

Referring now to the drawings, there is shown an embodiment of the present invention in the form of an electrically heated pressing iron 20 comprising a sole plate 22 preferably constructed of a cast metal such as aluminum, having its bottom surface and its sloping side edges polished or covered with a polished surface in order to present smooth clothes contacting surfaces. The sole plate 22 is heated by an electrical resistance or heating element 24 which preferably is of the sheathed type. Such types of heating elements are well known and generally comprise a helically wound resistance conductor 26 centrally disposed within an outer metallic sheath 28 and supported in spaced relationship in reference to the sheath by an electrical insulating heat conducting mass 30 (FIG. 3) formed of a suitable material such as highly compressed magnesium oxide. The sheathed heating element 24 is best shown in FIGS. 2, 3, and 7 of the drawings and has a generally U-shaped configuration or is roughly in the shape of a hairpin with the extremities of its legs disposed at the rear end of the sole plate, and with a bight portion disposed at the front or pointed end of the sole plate. Preferably the U-shaped heating element 24 is embedded in the sole plate 22 as by being cast therein during the process of casting the sole plate. As illustrated in the drawings and specifically in FIGS. 3 and 8 thereof, the sole plate 22 is provided with an integral upwardly extending U-shaped rib 32, in which the sheathed heating element 24 is received. The sheathed heating element 24 is, moreover, provided with suitable terminals 34 and 36 extending out of the metallic sheath, as best shown in FIG. 8 of the drawings, it being understood that these terminals are suitably connected to the centrally disposed resistance conductor 26.

For the purpose of defining a steam generating chamber which is in good heat transfer relationship with the heat-

ing element 24 through the rib 32 in which the heating element is disposed, the front portion of the sole plate 22 is provided with a steam generating chamber or well generally designated as 38. This steam generating chamber 38 is defined within the space bounded by the closed end of the U-shaped rib 32 and a vertical wall or cross member 40 (FIGS. 2 and 11) which extends between and effectively interconnects the two legs of the U-shaped rib 32.

In order that a satisfactory steam generating chamber may be defined which is closed to atmosphere except for the steam exit and water inlet pasageways, the adjacent top edge of the rib 32 enclosing the steam generating chamber 38 is provided with a flat ledge or sealing surface designated as 32a and best shown in FIGS. 2, 3 and 11, which is level with the top of the cross member 40 for supporting thereon a suitable steam chamber cover or closure plate 42 for the steam generating chamber 38.

FIG. 20 shows the cover 42 preferably comprises a three-layer construction as disclosed and claimed in Jepson Patent No. 2,871,587 and Jepson et al. Patent No. 2,906,043 and consisting of an upper rigid backing member 42a, an intermediate asbestos member 42b and a lowermost metal foil member 42c which may be formed of stainless steel or the like. All three of these members forming the cover 42 have a configuration corresponding with the shape of the ledge or sealing surface 32a. The rigid backing member 42a of the cover 42 is initially bowed so as to have a curvature which is concave downward as viewed in FIG. 2 whereby when drawn into sealing engagement with the ledge 32a by suitable fastening means, the cover will be stressed to provide a good seal around its entire periphery in engagement with the ledge 32a and the cross member 40. As best shown in FIG. 21, and claimed in Jepson et al. Patent No. 2,906,403, the three layers forming the cover 32 are held in assembled relationship by a valve body portion 43 of a flow or steam control valve shown generally at 44 and performing several functions including functioning as a valve member for regulating the flow of water into the steam generating chamber 38, and for securing the handle assembly to the sole plate. Specifically, the valve 44 includes the cylindrical valve body member 43 (FIG. 10) having a reduced portion 43a which extends through a cooperating opening defined in the upper rigid cover member 42a and is staked as indicated at 43b to secure the cover member 42a securely to the valve body 43.

The reduced portion 43a of valve body member 43 also extends through a cooperating opening defined in the asbestos member 42b of the cover 42 and the lower foil member 42c of the cover member 42 which are also secured in the unitary cover assembly as by staking 43c.

To secure the cover 42 to the steam chamber 38 in sealing relationship with the sealing surface 32a there are provided a plurality of screws or fastening means 48 and 49 which extend through the cover 42 and are each secured within tapped openings defined in the sole plate 22. In order to insure that only dry steam exits from the sole plate 22 of the iron 20, the steam generating chamber 38 is provided with various baffles integrally formed with the sole plate. These baffles, as best shown in FIG. 11, include a U-shaped raised portion 52 level with the ledge 32a having rearwardly extending legs or baffle members 52a and 52b which effectively divide the steam generating chamber 38 into a central portion and a surrounding U-shaped pasageway 54. A somewhat L-shaped baffle portion 52c extends from the leg 52b toward the leg 52a to define a tortuous steam pasageway. Where the two arms of the L of baffle portion 52c are joined, there is an enlargement 52d which has a tapped opening to receive the fastening means 49. Preferably the ends of legs 52a and 52b are provided with lateral projections 52e and 52f to further provide a labyrinth-like pasageway to insure the formation of dry steam.

The water supplied to the steam generating chamber 38

passes through the valve 44, the valve body 43 of which is secured to the cover plate 42, and enters this chamber adjacent the forward portion thereof, as is best shown in FIG. 2 of the drawings. Preferably the wall surfaces of the sole plate forming the steam generating chamber are treated by sandblasting and are coated with a thin coat of inorganic insulating material to provide an appreciable temperature drop at the surface of the steam generating chamber, thereby insuring that the water will wet these surfaces thus resulting in satisfactory steam generation. The water supplied to the steam generating chamber wets the treated bottom surface of the chamber and by virtue of the high temperature of this surface is immediately flashed into steam. This steam, which may contain some quantities of moisture, must first travel rearwardly in a tortuous path in the steam generating chamber as shown by the arrows in FIG. 11 and then forwardly through the U-shaped passageway 54 on both sides of the steam generating chamber in order to reach steam outlets or exits which comprise ports 62 located in the passageway 54. These ports 62 open to the bottom of the sole plate 22 and are collectively arranged in a sort of V-shaped configuration. To obtain distribution of the steam emerging through the ports 62 over a substantial area of the pressing surface of the sole plate 22, the ports 62 at the pressing surface are preferably flared as indicated at 62a and these flared portions are preferably interconnected by a plurality of elongated grooves designated as 64 (FIG. 2). These grooves may extend over a substantial portion of the bottom of the sole plate. Thus, the steam emerging from the flared ports 62 is spread over the material being ironed by the grooves 64 with the result that a substantial area of the bottom of the sole plate is covered with steam.

To facilitate assembly of a suitable thermostatic control device to be hereinafter described with the sole plate 22, the latter is provided with a well generally designated at 68, best shown in FIGS. 2, 9 and 11 of the drawings, which is defined between the legs of the U-shaped rib 32 enclosing the heating element 24. The well 68 is bounded at its forward end by a wall 70 extending transversely of the iron between the legs of the U-shaped rib 32 and is bounded at its rearward end by a vertical wall 72 also extending between the legs of the U-shaped rib 32. The vertical wall 72 includes a central rearwardly extending portion 72a for supporting portions of the thermostatic control device, as will become evident from the ensuing description. The wall 70 extends substantially parallel to the cross member 40, thus defining a well or recess 71 in the sole plate for isolating the thermostatic control element from the local temperature effects attendant upon formation of steam within the steam generating chamber 38. Moreover, the wall 70 further includes angularly disposed rear surfaces 70a diverging from the center of the sole plate 22 in order to provide relatively large heat conducting masses integral with the legs of the U-shaped rib 32 in which the heating element 24 is embedded thereby to effect maximum transfer of heat from the heating element 24 to the center of the wall 70 and to provide for effective operation of the thermostatic control device mounted upon this wall by insuring that the temperature of this wall 70 corresponds closely to the temperature of the ironing surface of the sole plate 22.

For the purpose of enclosing the upper part of the sole plate, there is provided a cover shell or heat reflecting barrier 73 of very shallow depth which is supported at the forward tip of the sole plate by a raised small area portion 74 integrally formed with the sole plate. The cover shell is further supported by pairs of lugs integrally formed with the sole plate and designated as 76, 78 and 80.

So that an operator may manipulate the pressing iron, there is provided a combined handle and reservoir generally designated as 82 and preferably formed of a molded heat and electrical insulating material such as one

of the many synthetic resins capable of withstanding relatively high temperatures. The handle and reservoir member 82 is of substantially D-shape and it comprises a hollow base or skirt portion 82a defining a water reservoir cavity 83 open at the bottom and a handgrip portion 82b. The bottom of the portion 82a has a configuration very much like that of the cover shell 73. A pair of somewhat vertical front and rear hollow posts 82c and 82d extend from the base portion 82a and are interconnected at their top by the handgrip portion 82b. The base portion 82a which substantially covers the top of the cover shell functions to shield the hand of the operator from radiated heat and, hence, provides for comfortable and efficient operation of the iron, and additionally as hereinafter described further functions as defining a substantial part of the water reservoir of the iron. The portions 82a, 82b, 82c and 82d are molded as a one-piece construction. A transversely extending wall 82e separates the water reservoir cavity 83 from a rear chamber 84, the cavities or chambers 83 and 84 communicating with their respective hollow posts 82c and 82d.

At the rear of the chamber 84 are a pair of enlarged bosses 82f disposed on opposite sides of the iron, and best shown in FIG. 2 of the drawings, and each including a tapped opening or a tapped insert molded therein for the purpose of receiving fastening screws 85 to secure the rear of the member 82 to the cover shell 73.

At the forward portion of the hollow front post 82c of the member 82 there is defined a filling opening 86 which communicates with the chamber or cavity 83. The outside wall of post 82c immediately adjacent filling opening 86 is sloped toward the opening as indicated at 82h to facilitate pouring water through this opening. This opening 86 is disposed immediately beneath a flat shelf-like portion 82g integrally molded with the remainder of the combined handle and reservoir 82. This shelf includes a somewhat oval-shaped aperture 87 (FIG. 6) affording access to valve 44, which aperture is closed by a removable plug 88 which may suitably be formed of molded neoprene rubber or the like. On top of this plug is a U-shaped bearing plate 93 preferably formed of nylon which is held in position by a depending lug 93a (FIGS. 2 and 4) receivable in a recess 88a defined in the top of plug 88.

For the purpose of defining the bottom wall of the water reservoir 83, there is provided a water reservoir plate cover 89. The cover 89 has a periphery in the shape of a closed U and conforms to the shape of the bottom opening in the member 82 forwardly of the transverse wall 82e. Suitable gasket means 90 partially disposed in a recess 91 defined of the member 82 is interposed between cover 89 and member 82 as clearly shown in FIGS. 2, 3, 6 and 7 of the drawings. The gasket 90 may be in the form as an O-ring, and insures a hermetic seal between the cover 89 and the combined handle and reservoir defining member 82, thereby forming the water reservoir 83.

To secure the cover 89 to the member 82, there are provided a plurality of screws or fastening means 94 (FIGS. 2 and 6) which engage tapped openings in the member 82—some of which are disposed in bosses 82f. It will be noted from FIG. 6 that sealing gasket 90 is distorted so as always to be positioned on the inside of the screws 94 so that there can be no leakage from the reservoir 83 around the screws 94. Extending between two of these bosses 82f is an integral baffle member or partial partition 82j depending from the top wall defining reservoir 83 and having its lower edge terminating short of the cover plate 89.

In order to provide fingertip control of both the steam flow and the temperature setting of the iron 20, the manipulating portions of these controls should be adjacent the top of hollow front post 82c of member 82. This means that if the thermostatic control mechanism described hereinafter is located within the cover shell 73,

some mechanically adjustable means must extend through reservoir 83. To this end there is provided a passageway 109 as defined by a tubular member 102, best shown in FIGS. 2, 3 and 5 of the drawings. The tubular member 102 extends vertically through the reservoir 83 and has its lower end hermetically sealed around the periphery of an opening 103 in the water reservoir cover 89. Specifically, the lower end of the tubular member 102 is provided with a shoulder 102a which is seated against the inner surface of the water reservoir cover 89, and the portion of tubular member 102 extending through opening 103 is turned or spun against the outer surface of the cover 89 to secure the tubular member 102 to the cover 89 in a watertight manner. The upper end of the tubular member 102 extends above shelflike member 82g through a suitable opening provided therefor in plug 88, and between the bifurcations of U-shaped bearing plate 93. A combined baffle and support member 104 of somewhat U shape is provided within reservoir 83 with one leg 104a of the U-shaped member spot welded or otherwise secured to the inside of water reservoir cover 89. The other leg 104b is provided with an opening for receiving and supporting tubular member 102. The bight portion of the member 104 prevents the rush of water from one end of the reservoir to the other during an ironing operation. However, passageways 105 (FIG. 3) beneath member 104 permit water in reservoir 83 to move from one side of member 104 to the other. The free end of leg portion 104b preferably engages a shoulder 106 defined beneath filling opening 86. Moreover, this leg portion 104b is provided with a flanged opening 107 for accommodating steam control means described hereinafter.

Thus far, only the valve body 43 of steam valve 44 has been described which controls the flow of water from the reservoir 83 to the steam generating chamber 38. As will be observed by reference to FIG. 10 of the drawings, the valve body 43 which has its lower end secured to the steam generating chamber cover 42, as previously described, is of generally cylindrical shape and is internally threaded as indicated at 108 to receive a combined valve seat and reservoir securing member 110 which latter member is externally threaded to engage the threads 108 of the valve body member 43. The member 110 is in effect a hollow bolt having a head portion 110a which is intended to engage to inside surface of reservoir cover 89 and extend through an opening 111 defined therein. The threaded portion 110b thereof is adapted to extend through an opening 112 in cover shell 73 aligned with the opening 111 so as threaded to engage valve body 43. A suitable hollow sealing washer 113, such as one formed of a silicone rubber, is compressed between the top of valve body 43 and the outside of reservoir cover 89 thereby to provide a sealed passageway from reservoir 83 to steam generating chamber 38. The washer 113 is also a heat insulator preventing the transfer of heat from the sole plate 22 to the member 82. It will be understood that member 110 secures the reservoir cover 89, and hence, member 82 secured thereto to the sole plate 22, via steam generating chamber cover plate 42. Preferably the head 110a of member 110 is provided with suitable tool engaging means whereby it may be manipulated by a tool extending through aperture 87.

The hollow lower end of the member 110 is provided with a small metering orifice 114 immediately above which is a tapered valve seat 115. A valve stem or needle valve element 116 is slidably received in the internal passageway of member 110 and has a tapered lower end 116a complementary with the tapered valve seat 115 so that when the valve 44 is closed as shown in FIG. 10 of the drawings, water is effectively stopped from passing through the steam control valve 44. At the lowermost end of the valve stem 116 there is provided a cleanout needle 116b which, upon movement from the open to the closed position, cleans out the metering orifice 114 thus

5 preventing the deposit of lime or other minerals which would otherwise tend to block this opening. Valve stem 116 extends through openings 107 and 87 and preferably through an opening 118 provided in plug 88 with the upper end of valve stem 116 being above the shelflike surface 82g.

10 It will be appreciated that during an ironing operation the iron is moved backwardly and forwardly in contact with the articles or goods being ironed, with the result that the water in the water reservoir 83 will tend to rush from one end thereof to the other. This is prevented by virtue of the baffles 82j and 104 already described. These baffles tend to cause the water in its movement due to the back and forth motion of the iron to move in a circular pattern in the reservoir 83. The portion 104b of baffle 104 prevents the splashing of this water out of the filling opening 86 in the handle post 82c.

15 To further prevent splashing from opening 86 during an ironing operation and to direct the flow of water around the valve stem 116 and the tubular member 102, there is provided an upper somewhat arcuate baffle member 122 (FIGS. 2 and 5) positioned just inside the filling opening 86 but having a plurality of passageways 124 through which filling water may pass. The baffle 122 is 20 positioned between the leg 104b of the baffle member 104 and the top of the front post 82c preferably having its front upper edge seated against a shoulder 126 integrally formed within member 82. As best shown in FIG. 5, the rear ends of the baffle member 122 engage shoulders 127 defined by post 82c. As illustrated, the baffle 122 is 25 positioned directly in front of the valve stem 116 and the tubular member 102 so that when the iron is upturned or resting on its rear end for filling, the filling water will be deflected around these components. Another generally V-shaped baffle or partial partition 82k formed integrally with the member 82 extends downwardly from the underside of the shelf 82g to a point quite close to portion 104b of baffle 104 to direct the filling water into the reservoir 83 and to prevent water from splashing from the reservoir 83.

30 To provide means for selectively controlling and maintaining the temperature of the sole plate 22 at any desired temperature, there is provided a temperature responsive control device generally designated at 128 and best shown in FIGS. 2, 8 and 9 of the drawings. This device must be capable of being accommodated within a relatively small space between the upper surface of the sole plate 22 and the bottom of the handle member 82 and water reservoir 83 within the handle, preferably within the shell 73. In accordance with the present invention, the temperature responsive control device 128 is supported so that it extends just forwardly of the rear wall 72 of the sole plate 22. Thus, the thermoresponsive control device 128 should 35 preferably be an elongated assembly extending beneath the water reservoir 83 and facilitating the use of a reservoir containing a large volume of water without appreciably increasing the outside dimensions of the iron, thereby permitting a very shallow shell 73 to be employed. Referring now to the drawings, the thermoresponsive control device 128 is essentially a subassembly including a supporting frame, a bimetallic element, a control switch, and numerous other necessary elements to be described in detail hereinafter. The supporting frame is designated generally by the reference numeral 130 and includes an elongated rectangular frame comprising a pair of side bars 130a interconnected at their upper edges near the front and the rear by horizontally extending crossbars 130b and 130c. The frame 130 is secured to the sole plate 22 by suitable fastening means 132 extending through crossbar 130b and clamping frame 130 to the top of the wall 70.

40 45 50 55 60 65 70 75 80 85 90 95 For the purpose of responding to the temperature of the sole plate 22, there is provided as part of the thermoresponsive control device 128 a main thermostat or bimetallic element 134 which has one end thereof clamped between crossbar 130b and wall 70 so as to be in intimate

heat exchange relationship with the sole plate 22. The bimetallic element 134 is thus secured in cantilever fashion and extends rearwardly of the wall 70. For the particular design disclosed in the drawings, the high expansion side of the bimetallic element 134 is on the bottom so that as the temperature of the sole plate rises the bimetallic element deflects upwardly. Preferably, there is secured to the free end of the bimetallic element 134 a contact actuating member 136 which is formed of a suitable electrically insulating material such as a ceramic. As was pointed out above, the mass of the wall 70 and tapered side portions 70a is sufficiently large to insure accurate correlation between temperature of the bimetallic element 134 and changes in the temperature of the sole plate 22.

In order to control an electrical circuit in response to the movement of the bimetallic element 134, the temperature responsive device 128 further includes a pair of relatively movable contacts 138 and 140. The lower contact 140 may be considered the stationary contact, since it does not move in response to the operation of the bimetallic element 134. This is somewhat of a misnomer, however, since it is selectively movable, as will become apparent from the following description, to adjust the temperature setting of the pressing iron of the present invention. The contact 138, on the other hand, may be considered the movable contact, since it is adapted to be moved in response to deflection of the bimetallic element 134.

For the purpose of supporting the relatively movable contacts 138 and 140 as a part of the subassembly 128, there is provided a stack of interposed insulating and conducting members, generally designated at 142, which stack is supported by a rivet or other fastening means 143 from a rearward extension of the frame 130. This stack 142, as in Jepson et al. Patent No. 2,906,043, supports in insulated relationship a pair of switch arms 144 and 146 supporting the contacts 138 and 140, respectively. The switch arm 146 includes a flexible portion 146a and a rigid portion 146b, the flexible portion tending to bias contact 140 downwardly as viewed in FIG. 2 of the drawings. The contact arm 144 is a flexible arm and also constantly tends to bias contact 138 downwardly as viewed in FIG. 2 of the drawings.

In order electrically to connect the terminals 34 and 36 of the sheathed heating element 24 in series with the switch comprising contacts 138 and 140, the stack 142 supports a plurality of bus bars 148, 150 and 152. The bus bar 148 includes a laterally extending arm 148a which by means of a conductor 154 electrically interconnects this bus bar with terminal 34 of sheathed heating element 24. The bus bar 148 also includes an upwardly extending arm 148b which extends upwardly through an opening 156 in shell 73 into chamber 84 where electrical connections with a conventional power cord as schematically indicated in FIG. 12 of the drawings can readily be made. The bus bar 150 is connected by a conductor 158 with the terminal 36 of sheathed heating element 24 and is also held in stack 142 in conducting relationship with switch arm 146. The bus bar 152 is held in stack 142 in conducting relationship with flexible switch arm 144 and includes a vertical extension 152a which extends through shell opening 156 into chamber 84. As shown in FIG. 12, the vertical bus bar extensions 148b and 152a are electrically connected by conductors 160a and 160b of a power cord 160 to a conventional plug connector 162.

For the purpose of preventing initial temperature overshoot of the sole plate 22 when first connected to a source of electric energy and to improve the load characteristic, the thermoresponsive control device 128 includes a compensating thermostat or bimetallic element, designated by the reference numeral 164, which is illustrated as a short plate riveted or otherwise secured to the end of the flexible switch arm 144 and extending into the path of movement of the contact actuating element 136. The com-

pensating thermostat 164 has its high expansion side disposed below the lower expansion side so that an increase in temperature will cause it to deflect upwardly. Since it is not in good heat transfer relationship with the sole plate 22, it will not deflect as rapidly initially as the element 134 until the ambient temperature in the iron has increased.

For selectively controlling the temperature of the sole plate 22 by selectively positioning the stationary contact 140, there is provided a cam rod 166 having an inclined cam surface 166a engaging a cam follower 170 supported on an extension 171 secured to the rigid portion 146b of contact arm 146. Since the extension 171 is electrically connected to the contact 140, the cam follower 170 is preferably of electrical insulating material. The cam rod 166 is illustrated as of generally inverted U-shaped cross section and has its bight portion at the rear of the iron slidably positioned on an adjusting screw 172 which passes through an opening in the rearward portion 72a of the rear wall 72 and which threadedly engages a resilient U-shaped speed nut 174, the legs of which are disposed on opposite sides of portion 72a. Rotation of the adjusting screw 172 permits calibration of the temperature control means in a manner as will hereinafter become apparent. The forward end of the cam rod 166 is guided for reciprocal movement by a control assembly bracket 178. The bracket 178 is secured to the cover 42 of the steam generating chamber 38 by the screw 49 which passes through an aperture in the bracket 178. As best seen in FIGS. 2, 3 and 8, the bracket 178 has an upstanding T-shaped portion 178a at one side thereof which has the stem portion thereof extending through an elongated slot 179 defined in cam rod 166. This T and slot arrangement permits guided longitudinal movement of cam rod 166.

In accordance with the present invention, one flange of U-shaped cam rod 166 is cut away in the area of the bracket 178, and the edge of the bight portion is provided with gear teeth 166b forming a rack. The bracket 178 is provided with a slightly elevated portion 178b (FIG. 3) upon which the inner surface of the bight portion of the cam rod 166 rides.

In order that the cam rod 166 may be accommodated within the relatively small space between the upper surface of the sole plate 22 and the bottom of the reservoir 83 and within shell 73, the cam rod 166 contains a bend 166c (FIG. 8) so that the forward portion comprising the rack may be positioned nearer the center of the iron near the forward end of the bight portion of the upwardly extending U-shaped rib 32. At the same time, the rearward portion, including the inclined cam surface 166a, is located away from the longitudinal center of the iron so as not to interfere with the temperature responsive device 128 but so that the inclined cam surface 166a engages the cam follower 170.

The operation of the thermoresponsive control device 128 is apparent from the foregoing description. However, briefly, when the follower 170 engages the lower portion of the inclined cam surface 166a, the flexible spring arm 146a biases the contact arm 146 and stationary contact 140 downwardly to the maximum extent. At the same time, the contact actuating member 136 on the bimetallic element 134 engaging the compensating thermostat 164 holds the movable contact 138 out of engagement with the fixed contact 140 thereby constituting a switch "Off" position. As the cam rod 166 is moved rearwardly, so that the cam follower 170 is raised along the inclined cam surface 166a, the fixed contact 140 is brought into electrical engagement with the movable contact 138 so as to complete a circuit as hereinafter described, thereby closing the switch formed by contacts 138 and 140. As the cam follower 170 is raised higher along the inclined cam surface 166a, movement of the bimetallic element 134 required to break the electrical engagement between the movable contact 138 and the stationary

contact 140 will be greater, thereby raising the temperature of the sole plate at which the contact actuating member 136 opens the switch formed by contacts 138 and 140. Moreover, as heretofore described, the compensating thermostat 164 including the bimetallic element compensates for changes in the ambient temperature of the thermoresponsive device 128.

For the purpose of securing the shell or cover 73 to the sole plate 22, there are provided suitable fastening means 190 (FIGS. 7 and 8) extending through openings in shell 73 and threadedly engaging tapped openings defined in circular bosses 192 formed integral with the sole plate 22 and projecting upwardly therefrom. The cover shell 73 has a portion 73a extending beyond the heel of the sole plate 22 thus providing a downwardly opening housing (FIG. 2) affording access to the fastening means 85 which, as described above, secure the rear of the handle and reservoir member 82 of the pressing iron to the shell 73. It will be recalled that the forward end of the member 82 is secured directly to the sole plate 22 of the iron 20 by the assembly of the steam valve 44 with the cover 42 of the steam generating chamber 38 and the bottom plate 89 of the water reservoir 83.

In order to close the downwardly directed chamber defined by the portion 73a of the cover shell 73 which provides access to fastening means 85, there is provided a suitable closure plate 198 of generally L-shaped cross section which is secured to the extension 72a on the sole plate 22 by fastening means 199. This closure plate is designed to provide a pleasing appearance and also a minimum path for heat transfer between the sole plate 22 and shell 73.

In order that the power cord 160 may enter the chamber 84 in member 82 to make electrical connections with rigid conductors 148b and 152a disposed in chamber 84, the rear of the member 82 adjacent post 82d is provided with an opening 200 (FIGS. 1 and 2). This opening 200 is in the form of an arcuate recess extending across the entire rear of post 82d. So that the power cord 160 supplying current to the iron may be made to extend laterally from either side of the iron depending upon whether the user is right- or left-handed, the cord opening 200 is provided with a cord opening closure 202 which is of such size and shape to completely fill the arcuate recess 200 and to provide a surface on all exposed sides thereof, except one, which conforms to the adjacent surfaces of member 82. On said one exposed side of closure 202, there is an opening for power cord 160 and a passageway therefor into chamber 84. This cord opening is at one end thereof as shown in FIG. 1 of the drawings. The closure 202 is symmetrical so it may be placed in the arcuate recess two different ways whereby the cord enters from the left side as shown in FIG. 1, or if reversed, the cord enters from the right. A suitable fastening means 204 (FIG. 2) holds closure member 202 in either of these two positions wherein the member 82 and closure 202 afford the appearance of a unitary structure. Suitable strain relief means are preferably provided as well as a helical spring 206 disposed concentrically with the cord 160. Preferably the closure 202 is formed of two complementary portions not shown whereby one end of spring 206 may be held between these complementary portions.

It will be appreciated that pressing irons today are used to iron a wide variety of materials such as the new synthetic materials, silk, wool, cotton, linen, and the like, all of which require different temperatures for best ironing thereof. For example, rayon requires a much lower ironing temperature than does linen. It is for this reason that means are provided selectively to control the temperature at which the pressing iron 20 operates. To this end means are provided for controlling the position of the cam rod 166, and, therefore, the position of the follower 170 on the cam surface 166a described above. It will be appreciated that if the cam follower 170 is moved

in an upward direction by some control means, it will raise the temperature setting of the iron and, of course, if the cam follower 170 is permitted to move downwardly in the direction of the resultant biasing forces of the resilient contact support arm portion 146a, the contact 140 will be moved downwardly and, hence, will lower the temperature setting of the iron.

For the purpose of selectively moving the cam follower 170 upwardly or permitting it to be biased downwardly to a greater or lesser extent, there is provided a pinion or gear 220 in meshing relationship with the gear teeth 166b on the rack formed on the cam rod 166. This pinion is secured to the lower end of a rotatable control rod 222 disposed within the passageway 100 of tubular member 102. To maintain control rod 222 in the position shown, the lower end thereof secured to gear 220 has a portion extending through an opening in the control assembly bracket 178 to which is secured means to prevent movement along the longitudinal axis but to permit free pivotal movement thereof. The control bracket assembly 178 is provided with a plurality of protuberances 178c on which the pinion gear 220 rests to form a relatively frictionless bearing surface for the gear 220, and upon which the latter is free to pivot. The upper end of rod 222 extends out of tubular member 102 and above the shelflike surface 82g.

So that the rod 222 may be readily pivoted about its longitudinal axis, there is secured to the upper end thereof a temperature control lever 224, best shown in FIG. 4 of the drawings. The control lever 224 is supported for pivotal movement immediately above the shelflike surface 82g, above plug 88 and on bearing plate 93. The control lever 224 is preferably made as a flat stamping and includes a lateral extension 224a to which may be attached a suitable manually engageable control knob 225. In order that the control lever 224 may pivot about the longitudinal axis of control rod 222, the pivotal end thereof is of semicircular configuration as indicated at 224b, but, in effect, comprises a pair of bifurcations defining a sort of circular bearing surface therebetween for engaging the upper end of the tubular member 102 above the shelflike surface 82g. Thus, the lever 224 pivots about the stationary tubular member 102. So as not to interfere with the valve stem 116, the lever 224 is provided with an arcuate slot 228, thus permitting pivotal movement of the lever 224 through an angle of one hundred eighty degrees without interfering with the valve stem 116. Moreover, the extension 224a of the lever 224 engages shoulders 229, best shown in FIG. 4 of the drawings in the two extreme positions thereof, the position of the lever 224 shown in FIG. 4 being the "Off" position thereof.

In order that the pivotal movement of the lever 224 causes corresponding pivotal movement of the control rod 222, there is provided a somewhat U-shaped spring clamp 230 which secures the lever 224 to the control rod 222. As best shown in FIGS. 3 and 4 of the drawings, the upper end of the control rod 222 is provided with two opposed flat faces 222a which are receivable in a cooperating rectangular opening 230a defined in the spring clamp 230. Furthermore, the spring clamp 230 is provided with a pair of downwardly directed tabs 230b which engage cooperating grooves or openings defined in the lever 224, best shown in FIGS. 2 and 4 of the drawings.

The position of the temperature control lever 224 determines the temperature at which the iron 20 will operate. Specifically, when the temperature control lever is rotated counterclockwise, as viewed from above (FIG. 4) to its most counterclockwise position there shown, the cam rod 166 is advanced to its forwardmost position so that the cam follower 170 is at the lowermost position of the cam surface 166a. The natural bias of the flexible arm portion 146a moves the fixed contact 140 down-

wardly out of engagement with the movable contact 138, regardless of the temperature of the iron, i.e., in the position of the control lever 224 shown in FIG. 4, the iron is in a positive "Off" position even though the iron is cold. As the temperature control lever 224 is rotated clockwise, as viewed in FIG. 4, the cam rod 166 is moved rearwardly through engagement of the teeth 166b of the rack with the pinion 226, and the cam follower 170 is moved up the inclined cam surface 166a thereby raising the position of the fixed contact 140. As soon as contact 140 engages the movable contact 138, the electrical circuit is established through the electrical sheathed element 24 to heat the iron. It will be appreciated that upon the initial heating of the iron, the ambient temperature acting on the compensating thermostat 164 is relatively low, and the compensating thermostat 164 will have deflected very little. As the sole plate 22 of the iron is heated by the heating element 24, the bimetallic element 134, which is in intimate contact with the sole plate 22, causes the contact actuating member 136 to be moved upwardly so that at the preselected temperature, the contact actuating member 136 engages the compensating thermostat 164 moving the movable contact 138 out of engagement with the fixed contact 140 and thereby breaking the electrical circuit through the heating element. It will be appreciated that as the temperature control lever 224 is moved further in a clockwise direction, the follower 170 will move higher up the inclined 166a and will move the fixed contact 140 higher. Therefore, as the fixed contact 140 is raised, the contact actuating member 136 must raise higher before it disengages the contacts 138 and 140 to open the switch formed thereby, and the iron will operate at an increased temperature. Moreover, it will be appreciated that as the iron 20 attains normal operating temperature, the ambient temperature about the compensating thermostat 164 will increase, and the thermostat will bend upwardly thereby compensating for any increase in bending of the bimetallic element 134 due to increased ambient temperatures. In this manner, the iron 20 is prevented from overheating during the initial heating period when the iron is first turned on. It will also be appreciated that after the circuit including the contacts 138 and 140 is broken due to the action of the contact actuating member 136, the heating element 24 will be disengaged from the source of electrical power and the iron will begin to cool. As the temperature of the iron drops, the bimetallic element 134 moves in a direction to lower the contact actuating member 136 thereby lowering the movable contact 138 into engagement with the fixed contact 140 and re-establishing the electrical circuit through the electrical resistance element 24.

An important feature of the present invention resides in the ability to calibrate the temperature setting at the factory or elsewhere when the iron is completely assembled. To this end, the adjusting screw 172 (FIG. 9), which is provided with a somewhat rounded upper end for engagement with the inner surface of the bight section of the cam rod 166, includes means whereby it may be adjusted by utilizing a suitable tool. Moreover, the closure plate 198 is provided with the opening 238 (FIG. 9) which is aligned with the adjusting screw 172 so that the tool may readily engage the adjusting screw 172. With this arrangement, the temperature at which the iron operates for a given setting of the temperature control lever 224 may be accurately and quickly calibrated without disassembly of the iron.

In order to enclose the portions of the temperature control mechanism described above and of the flow control device to be hereinafter described, and, in addition, to provide suitable indicia for indicating the position of the knob 225 of the temperature control lever 224, there is provided a temperature dial 239 which is shaped so as to provide an enclosure above the plug 88 and further to

form a continuation of the hand grip portion 82b of the member 82 to cause it to blend smoothly with the forward post portion 82c of the handle. Consequently, the temperature dial 239 is somewhat in the shape of a segment of a hollow sphere including a projection 239a extending rearwardly into a recess 240 defined in the handle member 82 (FIG. 2). When thus assembled to the iron, the temperature dial 239 leaves a narrow space or arcuate slot 241 between the bottom thereof and the shelflike surface 82g to permit pivotal movement of the control lever 224 therein. Preferably, the temperature dial 239 is provided with a skirt portion 239b on which skirt portion indicia may be provided such as an "Off" indication and an indication of settings for various kinds of material which are likely to be ironed by the pressing iron 20. A "steam" setting is also preferably provided. As illustrated in FIG. 1 of the drawings, this skirt is provided with the following indicia starting from the "Off" position of knob 225: "Off," "Rayon," "Silk," "Steam," "Wool," "Cotton," Linen."

Preferably the needle valve controlling the water flow between the reservoir 83 and steam generating chamber 38 comprising valve stem 116 has only two positions, namely, an open position and the closed position, shown in FIG. 10 of the drawings. To provide fingertip control of the needle valve 44, the upper end thereof disposed above shelflike surface 82g comprises a reduced neck section 116c receivable in a slot or groove in an actuating lever 242. The lever 242 extends through an elongated slot 243 defined in the temperature dial 239. Secured to the free end of the lever 242 is a manual steam control knob 244. The surface of the temperature dial 239 along the slot 243 rises from one end to the other and is provided with a knob depression 245 at the upper end thereof. The location of this knob depression 245 relative to the valve stem 116 is such that when the knob 244 is in the depression 245, the water control valve 44 is open, the valve stem 116 being raised. On the other hand, when the knob 244 is in the position shown in FIG. 2, the water control valve 44 is closed and in the position best illustrated in FIG. 10 of the drawings.

As illustrated in the drawings, the needle valve element 116 is normally urged in a downward or closed direction, as viewed in FIG. 2 of the drawings. To this end, biasing means in the form of a coiled spring 246 surrounding the needle valve stem 116 are provided compressed between the plug 88 and a lower washer 247 secured to the needle valve stem 116 by any suitable means. Preferably an upper washer 248 is interposed between spring 246 and the lower surface of the plug 88. With this construction the normally compressed spring 246 urges valve stem 116 in a downward direction to close valve 44.

It will be understood that the needle valve element 116 may be biased to the open position, if desired, instead of to the closed position, as illustrated. The illustrated arrangement is believed to be quite superior, however, since at least two distinct advantages occur as a result of having the spring 246 bias the needle valve element 116 to a closed position. First, the spring 246 provides a safety valve action so that if the openings in the sole plate become blocked, steam pressure may be released by merely forcing valve element 116 upwardly against the biasing force of the spring 246. Secondly, the spring 246 acting in this direction, permits wide manufacturing tolerances with respect to the distance between the seating portion of the valve element and the manual means for locking the valve in the nonbiased position. If the valve were biased to the open position, accurate machining of the element and seat would be necessary to insure that the manual means can lock the valve in a truly closed position.

In order that the water valve 44 be above the level of the water in the reservoir 83 when the iron 20 is in an upright or rest position, the lower end of the valve 44

including the valve stem 116 is inclined slightly forward of the upper end thereof. In this upended position, the water in the reservoir 83 will be below the valve 44 and the flow of water from the water reservoir 83 to the steam generating chamber 38 will be discontinued. Thus, it is not necessary that the valve 44 be closed in order to stop the steaming of the iron; it is merely necessary to set the iron in its upended or rest position.

From the foregoing explanation, it will be observed that the front vertical post of the plastic handle is made sufficiently large and the horizontal bottom portion of the handle has been extended downwardly so that the water reservoir 83 is fully contained in at least a portion of the handle. This permits the shell 73 to be reduced to a fraction of the size of the conventional shell. It will also be observed that although the water reservoir 83 is located within the member 82, nevertheless, the temperature control knob 225 and the steam control knob 244 are conveniently located near the top of the front post 82c near the forward end of the hand grip portion 82b of the member 82 and are readily and conveniently operable with facility by virtue of the fingertip control provided at closely adjacent positions near the top and front of the member 82. Moreover, these elements are located in the coolest area of the member 82, with the result that the problems caused by excess heat are avoided.

Also, it will be observed that the location of a major portion of the temperature responsive device 128 at the rear portion of the sole plate 22 and the use of the longitudinally movable cam rod 166 between the steam generating chamber 38 and the bottom cover 89 of the water reservoir 83 provide for more effective utilization of the space between the water reservoir 83 and the sole plate 22, and, hence, eliminate a bulky appearance of the iron. It further provides for the location of the device 128 as far as possible from the steam generating chamber 38, thus isolating this assembly from the adverse effects of temperature cooling as a result of steam formation.

In view of the detailed description included above, the operation of the steam and dry iron of the present invention will readily be understood by those skilled in the art and no further discussion thereof is included herewith.

While there has been shown and described a particular embodiment of the present invention, it will be apparent to those skilled in the art that various modifications may be made without departing from the invention in its broader aspects, and it is, therefore, aimed in the appended claims to cover all such changes and modifications as fall within the true spirit and scope of the present invention.

What is claimed as new and desired to be secured by Letters Patent of the United States is:

1. A pressing iron comprising a sole plate, handle means secured to said sole plate, electric heating means for heating said sole plate, temperature responsive means responsive to the temperature of said sole plate for controlling said heating means, cam means and a cam follower for adjusting said temperature responsive means selectively to control the temperature of said sole plate, manually operated means including an operating member selectively adjustable to different positions, indicating means for indicating the different positions to which said member is adjusted, means including a rack and a cooperating gear operatively interconnecting said manually operated means and said cam means, and adjustable means adjustably positioning said cam means for calibrating said temperature responsive means thereby to correlate the selected temperature of said sole plate with the selected indication of said indicating means.

2. A pressing iron including the combination of a sole plate, a handle secured to said sole plate, electric heating means for heating said sole plate, a thermal control device responsive to the temperature of said sole plate for controlling said heating means, means including a longitudinally movable cam rod having an inclined

cam surface and a cam follower cooperating with said cam surface for adjusting said thermal control device selectively to alter the temperature of said sole plate, said cam rod being disposed between said handle and said sole plate, and manually operated means including a member for longitudinally positioning said cam rod.

3. A pressing iron including the combination of a sole plate, a handle secured to said sole plate, electric heating means for heating said sole plate, a thermal control device responsive to the temperature of said sole plate for controlling said heating means, cam means including a longitudinally movable cam rod extending between said handle and said sole plate in a direction generally parallel with the ironing surface of said sole plate and having an inclined cam surface defined thereon, a cam follower cooperating with said cam surface, means responsive to the position of said cam follower for adjusting said thermal control device selectively to control the temperature of said sole plate, manual means operatively connected to one end of said cam rod, indicating means for indicating the different positions to which said manual means is adjusted, and means for adjustably positioning the other end of said cam rod to calibrate the operation of said thermal control device with said indicating means.

4. A pressing iron including the combination of a sole plate, a handle secured to said sole plate, electric heating means for heating said sole plate, a thermal control device responsive to the temperature of said sole plate for controlling said heating means, manually operated means including an axially movable cam rod having an inclined cam surface, a cam follower cooperating with said cam surface for adjusting said thermal control device to alter the temperature at which said thermal control device is responsive, indicating means for indicating the different positions to which said manually operated means is adjusted, means slidably mounting one end of said cam rod, threaded adjusting means for adjusting the position of the other end of said cam rod relative to said cam follower for correlating the temperature of the sole plate and the indications provided by said indicating means, closure means associated with said handle and said sole plate affording access to space above said sole plate, and an opening in said closure means in substantial alignment with said threaded means to permit the insertion of a tool through said opening for manipulating said adjusting means.

5. The pressing iron of claim 4 wherein said cam rod is of inverted U-shape cross section with a bight portion and leg portions, and wherein said bight portion slides on said threaded adjusting means.

6. The pressing iron of claim 2 wherein a shallow shell is secured to the top of said sole plate enclosing said thermal control device, cam rod and cam follower.

7. A steam iron comprising a sole plate, electric heating means for said sole plate, switch means for controlling the temperature of said sole plate, supply conductors for electric current for said heating means, a one-piece plastic handle secured above said sole plate, said handle having spaced hollow front and rear posts and a hand grip spanning the space between said posts across the upper ends thereof, said handle also having a lower hollow skirt portion spanning the space between said posts across the lower ends thereof, said hollow skirt portion having an open bottom and an integral partition dividing said hollow skirt portion into a first and a second compartment, a sealing plate for the open bottom of said first compartment to define a water reservoir, said second compartment being open at one end and comprising a portion extending into said hollow rear post, and electric conductors extending from said supply conductors down through said hollow rear post and second compartment to said heating means and switch means, said front compartment comprising a downwardly extending baffle molded integral with said handle to retard the movement of water in said front compartment during ironing.

8. The iron of claim 7 wherein said hollow front post has a molded filling opening facing forward and located adjacent the top end of said front post.

9. The iron of claim 7 wherein there is provided a hollow member extending from the top of said front post through the first compartment to said sealing plate, a control rod extending through said hollow member, said hollow member having watertight connections with at least said sealing plate so as to keep water away from said control rod extending through said hollow member.

10. The team iron of claim 7 wherein there is provided in said front compartment a tubular member engaging said sealing plate and a control rod associated with said switch means extending through said tubular member, said

tubular member having watertight connections with at least said sealing plate so as to keep water away from said control rod extending through said tubular member.
